(57) **CLAIM**

The design for a convertible top frame, as shown and described.

DESCRIPTION

FIG. 1 is a top left side perspective view of the convertible top frame;

FIG. 2 is a top right side perspective view of the convertible top frame;

FIG. 3 is a front side elevational view of the convertible top frame;

FIG. 4 is a rear side elevational view of the convertible top frame;

FIG. 5 is a left side elevational view of the convertible top frame;

FIG. 6 is a right side elevational view of the convertible top frame;

FIG. 7 is a top plan view of the convertible top frame;

FIG. 8 is a bottom plan view of the convertible top frame;

FIG. 9 is a top rear left side perspective view of the convertible top frame in the folded position;

FIG. 10 is a top left side perspective view of the convertible top frame in the folded position;

FIG. 11 is a top rear right side perspective view of the convertible top frame in the folded position;

FIG. 12 is a top right side perspective view of the convertible top frame in the folded position;

FIG. 13 is a front side elevational view of the convertible top frame in the folded position;

FIG. 14 is a rear side elevational view of the convertible top frame in the folded position;

FIG. 15 is a right side elevational view of the convertible top frame in the folded position;

FIG. 16 is a left side elevational view of the convertible top frame in the folded position;

FIG. 17 is a top plan view of the convertible top frame in the folded position; and,

FIG. 18 is a bottom plan view of the convertible top frame in the folded position.

Portions of the vehicle roof and convertible top frame are shown in broken lines for illustrative purposes only and form no part of the claimed design.

1 Claim, 18 Drawing Sheets
